(57) **CLAIM**

We claim the ornamental Design for an ergonomic disposable plate sidewall, as shown and described. Broken lines in the Figures form no part of the claimed design.

DESCRIPTION

FIG. 1 is a perspective view of an ergonomic disposable plate sidewall;
 FIG. 2 is a front elevation view of the plate of FIG. 1, with an opposite view being identical thereto;
 FIG. 3 is a side elevation view of the plate of FIG. 1, with an opposite view being identical thereto;
 FIG. 4 is a top plan view of the plate of FIG. 1;
 FIG. 5 is a bottom plan view of the plate of FIG. 1;
 FIG. 6 is a cross-sectional front view of the plate of FIG. 1, with an opposite view being identical thereto; and,
 FIG. 7 is a cross-sectional side view of the plate of FIG. 1, with an opposite view being identical thereto.
